UNITED STATES PATENT OFFICE.

EDWARD E. KLEINSCHMIDT, OF LONG ISLAND CITY, NEW YORK, ASSIGNOR, BY MESNE ASSIGNMENTS, TO MORRUM-KLEINSCHMIDT CORPORATION, OF CHICAGO, ILLINOIS, A CORPORATION OF DELAWARE.

SELECTIVE MECHANISM.

Application filed February 7, 1923. Serial No. 617,572.

To all whom it may concern:

Be it known that EDWARD E. KLEINSCHMIDT, a citizen of the United States, residing at Long Island City, in the county 5 of Queens and State of New York, has invented certain new and useful Improvements in Selective Mechanism, of which the following is a specification.

This invention relates to selective mechanisms of the character in which a plurality of mechanical operations are selectively controlled from a remote point, such as motor control; switching operations and the like. It is particularly useful in printing telegraph machines, and the preferred embodiment herein disclosed is shown and described in its relation to a printing telegraph machine, such as shown in copending application Serial Number 530,880, filed 20 January 21, 1922.

The present invention involves improvements in the type of selector disclosed in the above mentioned application, and has for its object, the production of a simplified and 25 more efficient mechanical structure. A further object is the production of a selector in which a complete overlap is obtainable, without the use of storing frames or carriers previously in common use, and 30 without the necessity of resorting to intermediate members used by other well known types of mechanisms. By "overlap" is to be understood the operation of a mechanism in which a succeeding selective combination 35 is received while the preceding selective operations are being completed. This results in a considerable increase in the speed of operation.

These and such other objects of the invention as will hereinafter appear, are attained in the preferred embodiment herein described, and shown in the accompanying drawings in which:

Fig. 1 is a front elevation of the selector mechanism with a portion broken away.

Fig. 2 is a plan view.

Fig. 3 is an end elevation showing the operating and restoring mechanism.

Fig. 4 is a fragmental view showing the 50 control of the selector bars.

Fig. 5 is a fragmental view showing the operating armature.

Fig. 6 is a sectional view taken on line AA of Fig. 2 looking to the right.

Fig. 7 is a sectional view taken on line 55 AA of Fig. 2 looking to the left.

Fig. 8 is a sectional view with parts broken away to show the locking mechanism.

As is well understood in the art, incoming selective combinations of electrical impulses are distributed in proper sequence to selector magnets 1 to 5. Individual to each selector magnet is an armature 6 (Fig. 2). Armatures 6 are pivotally mounted at 7 (Fig. 7) in slots 8 on supports 9, and are limited in movement by adjustable stop members 11. Springs 10 normally hold armatures 6 against stops 11. Mounted on armatures 6 are extensions 12. Extensions 12, at their ends are engaged by adjusting members 13. Members 13 are pivotally mounted at 14 (Fig. 1) on supporting member 15. Set screws 16 (Fig. 1) engage slots in members 13. In assembling the selector 75 mechanism, members 13 are adjusted about pivotal points 14 until armature extensions 12 are in proper relation with respect to selector bars 17 to 21 inclusive (Fig. 2), and screws 16 are then tightened to clamp members 13 in place. Due to the pivotal mounting of armatures 6 in slots 8, and a slight side movement permitted by the looseness of mounting on support 9, adjustment of the extension members in the direction of 80 the length of the selector bars may thus be made.

A series of five slots 22 (Fig. 1) are cut into the lower edge of bars 17 to 21. The slots in bar 17 are placed in such a manner, 90 that with magnet 1 de-energized and armature 6 thereof in retracted position, the shoulder formed by the first slot to the right in Fig. 1 engages armature extension 12 of magnet 1 to hold bar 17 to the left in unselected position. The remaining four slots are positioned in such a manner that bar 17 95 clears the extensions 12 of magnets 2 to 5 on movement of 17 in either direction. The slots on the remaining bars are positioned in 100

similar manner, so that armature extension 12 of magnet 2 acts as a stop to hold bar 18 in unselected position, and magnets 3, 4 and 5 control bars 19, 20 and 21 respectively. It will be apparent that each extension 12 acts as a stop to retain a single selector bar against motion while permitting free motion in both directions of the bars not controlled thereby. Selector magnets 1 to 5 control bars 17 to 21 respectively. Springs 23 are carried by a bevelled block 24 supported adjustably by screws 25 and 26. The tension of springs 23 may be simultaneously adjusted by adjusting screws 25 and 26.

Extensions 27 (Figs. 1 and 7) of armatures 6 extend rearwardly and downwardly and are engaged by latch members 28. Latch members 28 are pivotally mounted on spindle 30 (Figs. 7 and 8) extending across the mechanism rigidly supported in lugs 31 and 32 (Figs. 1 and 8), and held in properly spaced relation by slots 33 in guide plate 34 (Fig. 1). Springs 35, fastened to supports 9 by clips 36 and pins 37, hold latches 28 in engagement with extensions 27. Pins 37 extend through openings in extensions 27 and springs 35 are fastened thereto. As armatures 6 are attracted by magnets 1 to 5, extensions 27 slide over shoulders 38 of latches 28 (Fig. 7) and latches 28, moving under the influence of springs 35, lock the actuated armatures 6 in attracted position.

As any one of the latches 28 moves upwardly on energization of the respective selector magnet it actuates bail 39 (Figures 1, 2 and 7). Bail 39 extends across all of the latches 28, and at its ends is bent at right angles forming arms 40 and 41 which are rigidly fastened to collars 42 and 43. Collars 42 and 43 are fastened to spindle 44 (Fig. 8) rotatably mounted in supports 31 and 32, and as 39 is raised by latches 28, 44 is rotated. Rigidly fastened to 44 is a rocking member 45 (Figures 6 and 8) and loosely mounted on 44 is locking member 46. Integral with 46 is a projection 47. To collar 48 (Fig. 8) rigidly fastened to 44, is fastened a helical spring 49. Spring 49 forces member 46 forward to hold lug 47 in contact with rocking member 45. Toe 50 of rocking member 45 is adapted to be engaged by the teeth of ratchet wheel 51 (Figures 6 and 8). Ratchet wheel 51 is rotatably mounted on spindle 52, carried by support 32, and as it rotates member 45 is rocked and actuates bail 39. With armatures 6 in normally retracted position, bail 39 rests on latches 28, locking member 6 is thrown forward, and toe 50 is disengaged from ratchet wheel 51.

After magnets 1 to 5 have been controlled in accordance with an incoming selective combination of signals, a local impulse is sent by the usual distributor to operating

magnet 53. Armature 54 of magnet 53 is pivotally mounted on support 55 and held in normally retracted position against stop 56 by spring 57. Locking member 46 is normally positioned beneath a block 59 carried by an extension 58 of armature 54, and prevents actuation thereof until one of the armatures 6 has been actuated. When an armature 6 is actuated, the corresponding latch 28 raises bail 39 and rocks 44, thereby moving 46 out from under block 59 to permit movement of armature 54 when a local impulse is received by 53. Extension 58 carries a projection 60 (Figure 5) and a screw 61 locked in place by a lock nut.

Pivotally mounted on support 63, at points 64 is a selector bar locking member 66. Member 63 is bent upwardly to form an extension 67 (Fig. 4) adapted to engage shoulders 68 and 69 on the lower surface of selector bars 17 to 21. An extension 70 of member 66 is fastened to spring 71, the lower end of which is attached to a pin 72 projecting from support 63. (Figures 1 and 3.) Under the influence of spring 71, member 66 is pressed upwardly against the selector bars and engages shoulders 68 or 69, depending on the position of the respective selector bars.

Restoring member 75 is pivotally mounted at its lower end in support 63 at 76. Restoring pawl 77 is pivotally mounted at 78 on the upper end of members 75. Projecting from pawl 77 is a stop member 79 carrying a pin 80. A spring 81, fastened to pin 80 at its upper end and to a pin 82 at its lower end normally maintains pawl 77 in raised position engaging selector bars 17 to 21 with stop 79 against member 75. It will be apparent that stop 79 in this manner limits upward motion of pawl 77 under influence of spring 81. Screw 61 extends through an opening in pawl 77 and acts as a stop to limit the pivotal movement of member 75 away from the selector bars. Extending from member 75 is an operating pin 83. Operating pin 83 is engaged by an extension 84 of a printing frame 85, of a printing telegraph machine, such as is disclosed in the co-pending application, Serial Number 530,880, above mentioned. A spring 85 resiliently connects extension 84 with restoring member 75. As disclosed in the co-pending application, printing frame 85 is pivotally mounted at 86 and on a forward stroke thereof a selected pull bar 87 drops into aligned slots of the selector bars and is actuated to print a selected character.

The operation of the printing frame is controlled by closure of contacts 88 and 89. Contact 89 is mounted on a spring member 90, normally tending to separate 89 from 88. An arm 91 (Fig. 3) pivotally mounted at 92 controls spring member 90. An oper-

ating member 95 for arm 91 is pivotally connected to ears 93 on arm 91 at 94. Member 95 extends vertically, and extension 96 thereof passes through a guide hole in block 59 and armature extension 58. As armature 54 nears the end of an energizing stroke, block 59 engages shoulders 97 of member 95 and presses 95 downwardly. Actuation of 95 moves arm 91 to close contacts 88 and 89. 5 A latch arm 98 pivotally mounted at 99 to a block 100 is normally held against the end of arm 91 by a spring 101. As contacts 88 and 89 are closed, the end of 91 moves downward until recess 102 permits spring 101 to 10 move latch 98 inwardly thereby locking contacts 88 and 89 in closed position, as shown in Fig. 3. As printing frame 85 nears the end of its stroke, an extension 103, carried thereby engages the upper end of arm 98 and releases arm 91, thereby permitting contacts 88 and 89 to restore to normally open 15 position.

Pivotally mounted on block 59, carried by armature extension 58, is an actuating pawl 25 member. A spring 105 normally holds pawl tooth 106 in engagement with ratchet wheel 51. As armature 54 is depressed, tooth 106 rides over the following tooth of ratchet wheel 51, and as armature 54 retracts under 30 influence of spring 57, when magnet 53 de-energizes, ratchet wheel 51 is stepped and rocks member 45. Movement of 45 actuates bail 39 to release armatures 6, and condition selector magnets 1 to 5 to receive a succeeding selection.

Operation.

In event none of the magnets 1 to 5 inclusive are energized by incoming impulses, 40 member 46 remains positioned under block 59, and although a local impulse is sent to operating magnet 53, actuation of armature 54 is prevented. However, if any of the 45 magnets 1 to 5 are energized, the respective armatures 6 are attracted, and members 27 are moved to permit actuation of the corresponding latch members 28. Upward movement of any one of the members 28 actuates bail 39 to rock member 45 on spindle 50 44 and holds 39 in upward position. Movement of 45 removes the end of 46 from under block 59 to permit actuation of armature 54. 46 is held in removed or actuated position until latches 28 are restored. Upward movement of latches 28 also causes extensions 27 to slide over shoulders 38 and locks armatures 6 in attracted position. Assuming that magnets 1, 3 and 5 are actuated by an incoming combination of electrical impulses, 55 their armatures 6 will be locked in attracted position. Extensions 12 of these magnets will therefore be withdrawn from slots 22 of selector bars 17, 19 and 21. Normally,

locking member 66 holds selector bars 17 to 21 in unselected position. After the armatures of magnets 1, 3 and 5 have been set, a local impulse is sent to operating magnet 53. Since locking member 46 has been actuated, armature 54 is attracted. Movement of armature 54 first causes projection 60 to 65 disengage pawl 77 from selector bars 17 to 21, and then causes screw 61 to disengage locking member 66 from shoulders 68. As member 66 is depressed, selector bars 17, 19 and 21 are moved to the right in Fig. 1 under 70 the influence of springs 23. Since magnets 2 and 4, have not been energized, extensions 12 of their armatures remain in slots 22 and engage the shoulders formed thereby in bars 18 and 20. Bars 18 and 20 are therefore 75 held against movement. Movement of bars 17, 19 and 21 aligns a series of slots in well known manner to permit selection of an actuating bar 87.

After movement of bars 17, 19 and 21 has 80 been permitted, further movement of armature 54 causes block 59 to engage shoulders 97 on bar 95 and rocks arm 91 to close contacts 88 and 89. As contacts 88 and 89 are 85 closed, latch member 98 locks them in closed 90 position. Closure of contacts 88 and 89 causes printing frame 85 to move forward. Forward movement of 85 permits a bar 87 to drop in the aligned slots, and then moves bar 87 forward in the aligned slots to print 95 a character. Forward movement of frame 85 causes 84 to stress spring 85' and thereby move restoring member 75 to the left in Fig. 4. As pawl 75 was depressed and 66 released, bars 17, 19 and 21 moved to the 100 left in Fig. 4, and over pawl 77. As movement of 75 under the influence of spring 85 continues, pawl 77 is disengaged from the selector bars and moved upward under influence of spring 81 in a position to re-engage 105 the ends of the selector bars for restoration on the restoring stroke of 85. Movement of 75 is limited by engagement of pawl 77 with screw 61.

The local impulse sent to magnet 53 is 110 momentary, but of sufficient duration to actuate armature 54 completely. While frame 85 is being actuated to print a character, armature 54 restores under the influence of spring 57, permitting member 66 to lock bars 115 17 to 21 in their selective positions. Further upward movement of 54 causes pawl member 104 to actuate ratchet wheel 52, causing bail 39 to depress latches 28 which have been raised and thereby release armatures 120 6 of magnets 1, 3 and 5. These armatures restore partially, until members 12 engage the lower edges of bars 17, 19 and 21 which have been locked in actuated position. Sufficient movement of the armatures is permitted 125 to free members 27 from engagement

with shoulders 38, thereby immediately placing all the selector magnets in condition for a succeeding selection. Assuming that on the next selection, magnets 1 and 4 are energized, their armatures 6 will be locked in attracted position, and bail 39 will again be raised by latches 28.

As frame 85 approaches the end of the printing stroke, member 103 engages latch member 98, and releases contacts 88 and 89. Opening of contacts 88 and 89 cause printing frame 85 to restore under the action of its spring. Restoration of frame 85 first raises bars 87 from engagement with the selector bars, and then member 84 in engagement with pin 83 forces member 75 to the right in Fig. 4, causing pawl 77 to engage the actuated bars 17, 19 and 21, and moves these bars to unselected position. Armatures 6 of magnets 1 and 4 have been locked in actuated position by energization of these magnets. Armatures 6 of magnets 3 and 5, however, are now free to and do restore completely by moving into slots 22 on the restoration of bars 19 and 21. Bars 19 and 21 will therefore be held against movement until armatures 3 and 5 are again energized in a selection.

As soon as the printing frame has completely restored, and has restored the actuated ones of bars 17 to 21, another local impulse may be sent to magnet 53. Bars 17 and 20 will move under the influence of springs 23 and bars 18, 19 and 21 will be held against movement. Printing and the overlap selection of the succeeding character will proceed in the above described manner.

It will be apparent that a simplified selecting mechanism has been described, in which a complete overlap within the selector is secured, without the interposition of storage or intermediate members between the selector magnet armatures, and the selector bars. It will also be apparent that the succeeding character may be set up on the selector magnets before the actuating bar previously selected is removed from the aligned slots of the selector bars.

Having described a preferred embodiment of the invention what is desired to be secured by Letters Patent, and is claimed as new, is:

1. In a selective mechanism, a plurality of selectively movable members; means responsive to selective combinations of electrical impulses controlling selective setting movement of said members; releasing means for permitting the setting movement of the selected members; and control means between said first mentioned and said releasing means; said releasing means controlling said first mentioned means through said control means to permit response of said first mentioned means to a succeeding selective

combination of impulses, while said members are still set in accordance with the preceding selective combination.

2. In a selective mechanism, a set of normally locked, permutation bars movable in selective combinations; means responsive to combinations of electrical impulses for selectively releasing said bars; a magnet controlling the setting of the selected bars; restoring means for said bars; and control means between said first mentioned means and said control magnet; said control magnet controlling said first mentioned means through said control means to permit response of said first mentioned means to a succeeding selective combination of selective impulses, while said permutation bars are still set in accordance with the preceding selective combination, whereby a complete overlap of signals is secured.

3. The combination as set forth in claim 2 in which the means responsive to the combinations of impulses comprise a plurality of electro-magnets.

4. In a selective mechanism, a plurality of selector magnets; a plurality of longitudinally movable, notched selector bars directly and selectively controlled by said magnets; means common to and controlling the setting of said selector bars; and means controlled by said common controlling means to permit a succeeding selection to be received by said magnets while said selector bars remain set in accordance with the preceding selective operation.

5. The combination as set forth in claim 4 in which the common controlling means comprises an electro-magnet.

6. In a selective mechanism, a plurality of selector magnets operable in selected combinations, armatures individual to said magnets, a plurality of selectively movable, notched selector bars controlled by said armatures, latches for locking said armatures in retracted position, actuating means controlled by said selector bars, a restoring device for said bars operated by said actuating means, a controlling magnet and means operated thereby for successively controlling the setting of said selector bars, initiating the operation of said actuating means and controlling said latches to place the selecting magnets in condition to receive a succeeding selective combination before said restoring device functions to clear the selector bars of the preceding selective combination.

7. The combination as set forth in claim 6 and in which said actuating means comprises a plurality of printer actuating bars and a common operating member for said bars.

8. In a printing telegraph machine, a plurality of selector bars embodying a plurality

- of slots and adapted to be moved in various combinations to selectively align said slots; a plurality of actuating bars selectable by movement into said aligned slots; a plurality of selector magnets responsive to code combinations of electrical impulses and directly controlling said selector bars; and means permitting a succeeding selective operation to be initiated on said selector magnets before the actuating bar selected by the preceding selective operation has been withdrawn from the previously aligned slot.
9. In a selective mechanism; a plurality of longitudinally movable notched selector members; a plurality of members selectable by movement into the aligned notches of said selector members; actuating means for said selector members; a plurality of movable control members for said selector members; a plurality of electro-responsive devices controlling said control members; and means to secure an overlap in said selective mechanism, comprising means to permit a partial restoration only of operated ones of said control members before said selector members are restored.
10. In a selective mechanism; a plurality of longitudinally movable notched selector bars; a plurality of members selectable by movement into the aligned notches of said selector members; actuating means for said selector bars; a plurality of selector magnets; armatures individual to said selector magnets and controlling said selector bars; and means to permit partial restoration only of said armatures before restoration of said selector bars and complete restoration only after said bars are restored, whereby an overlap of selections in said selective mechanism is secured.
11. In a selective mechanism, a plurality of selectively movable selector bars; actuating means for said selector bars comprising a plurality of springs, one individual to each selector bar; a plurality of electromagnets controlling movement of said selector bars; and means for simultaneously adjusting the tension of said springs.
12. In a selective mechanism, a plurality of selectively movable bars; actuating means for said bars; a plurality of movable members controlling selective movement of said bars; electro-responsive means controlling movement of said movable members; and means for adjusting said movable members in the direction of movement of said bars.
13. The combination as set forth in claim 12 in which the electro-responsive means comprises a plurality of electro-magnets, and the movable members comprise armatures for said magnets.
14. In a selective mechanism, a plurality of selectively movable bars; actuating means for said bars; a plurality of movable members controlling selective movement of said
- bars; electro-responsive means controlling said movable members; locking means for said movable members, and releasing means for said locking means comprising a ratchet mechanism operated by said actuating means.
15. The combination as set forth in claim 14 in which the actuating means comprises an electro-magnet, and an armature for said electro-magnet actuating said ratchet mechanism.
16. In a selecting mechanism; a plurality of selector bars movable in selective combinations; means for moving said bars to selected position; means for restoring said bars to unselected position comprising a pawl adapted to engage said selector bars during restoration; and means for disengaging said pawl from said bars to permit movement of selected ones of said bars.
17. The combination as set forth in claim 16, and a plurality of actuating bars controlled thereby.
18. The combination as set forth in claim 16 and a lock for said selector bars controlled by said pawl disengaging means.
19. In combination, a selecting mechanism comprising a plurality of selector magnets controlling selector bars movable in selective combinations; means for moving said bars to selected position; means for restoring said bars to unselected position; a plurality of actuating bars controlled by said selecting mechanism, and a common operating member for said actuating bars controlled by said selecting mechanism, and mechanically actuating said selector bar restoring means.
20. The combination as set forth in claim 19 in which said operating member directly actuates said restoring means.
21. In combination in a printing telegraph receiver, a set of longitudinally movable, notched permutation bars, springs for effecting the setting movements of said bars, a common restoring device for the bars, a plurality of members selectable by movement into the aligned notches of the bars, a common actuating member for said selectable members and for said restoring device, a set of controllers for holding said bars in normal position and adapted to be set in different combinations in accordance with the received signals, a magnet individual to each controller, and controlling means for initiating the operation of said actuating member and for conditioning said controllers to permit the further operation thereof in advance of the restoration of said permutation bars.
22. In combination in a printing telegraph receiver, a set of longitudinally movable, notched permutation bars, springs for effecting the setting movements of said bars, a common restoring device, a set of individual controllers normally preventing the setting

movements of said bars, a magnet individual to each controller, a plurality of members selectable by movement into the aligned notches of said bars, a common operating member for successively actuating the selected member and said restoring device, means responsive to receive signals for selectively releasing said controllers, and controlling means for successively releasing said

restoring device, initiating the operation of said actuating member and conditioning said controllers to permit the further operation thereof in advance of the complete operation of said actuating member.

Signed this 31st day of January, 1923, at ¹⁵ Long Island City, New York.

EDWARD E. KLEINSCHMIDT.
